[57] ABSTRACT

A structural truss has upper and lower wooden chords separated along their lengths by vertical wooden struts. The chords and struts are joined together to form the truss frame solely by adhesive-backed paper membranes covering the opposite sides of the frame so as to transmit tensile stresses within the frame. The truss may be manufactured in multiples of various lengths by a continuous assembly line process.

STRUCTURAL TRUSS CONSTRUCTION WITH MEMBRANE COVERINGS

BACKGROUND OF THE INVENTION

1. Field of the Invention

The present invention relates to structural trusses and a method of manufacturing the same.

2. Description of the Prior Art

Conventional wooden structural trusses, such as roof and floor trusses used in the building industry, are made of long upper and lower wooden chords separated by a combination of vertical and diagonal wooden struts joined to the chords by nails or metal truss connector plates. Such conventional trusses are relatively heavy because of the large number of wooden struts they contain and also because of the large amount of metal in them, particularly when truss connector plates are used. They are also expensive because each such truss is custom made, either at the job site or at a nearby factory. Because of ever-rising building costs, there is a need for an inexpensive, lightweight, yet relatively strong structural truss suitable for use in residential and light commercial building construction.

SUMMARY OF THE INVENTION

The foregoing needs are met by the present invention which comprises a structural truss composed of the usual upper and lower chord members separated by upright struts. However, the truss of the invention is unique in that it does not contain the usual metal fasteners joining the struts and chords nor the usual diagonal struts. Instead, the chord and vertical strut truss frame described is covered on both sides by continuous adhesive-backed paper membranes which are joined to both the struts and the chords to hold such members in abutting relationship. Thus external loads applied to the truss are transmitted within the truss in tension primarily by the membranes, whereas compressive stresses within the truss are transmitted by the chords and vertical struts. The result is a structural truss which is reasonably strong, lightweight and inexpensive to manufacture, transport and erect. The membranes are made of paper of various tensile strengths depending on the need and are preferably treated for weather protection and to retard deterioration.

The truss may be conveniently manufactured continuously in an assembly line process by moving parallel chord lengths from a continuous finger jointing machine along horizontal paths, applying one of the adhesive-backed membranes to one side of the chord lengths at a first station, inserting the struts at intervals between the chord lengths and onto the membrane at a second station, applying the second membrane to the opposite sides of the struts and chord lengths at a third station, then curing the adhesive-backed membranes to join the structural members into a relatively rigid truss frame at a fourth station, and finally at a fifth station cutting the resulting continuous frame into sections of predetermined length.

Primary objects of the invention are to provide a structural truss which is strong and durable, yet lightweight and inexpensive to manufacture, transport and install.

BRIEF DESCRIPTION OF THE DRAWINGS

The foregoing objects, features and advantages of the

invention will become more apparent from the following detailed description which proceeds with reference to the accompanying drawing wherein:

FIG. 1 is a side elevation of a structural truss in accordance with the invention with portions of both covering membranes removed for clarity of illustration;

FIG. 2 is a side elevational view on a smaller scale of a conventional structural truss of the prior art;

FIG. 3 is a vertical sectional view taken along the line 3-3 of FIG. 1 on an enlarged scale; and

FIG. 4 is a schematic side elevational view illustrating a method or apparatus for manufacturing the truss of FIG. 1.

DETAILED DESCRIPTION

With reference to the drawing, a conventional truss 10 of the prior art is shown in FIG. 2 composed of an upper chord member 12, a lower chord member 14, vertical struts 16, right diagonals 18 and left diagonals 19. The various vertical and diagonal struts are joined to the chords by metal truss connector plates 20. Such plates are well known in the art and usually consist of, heavy-gauge sheet metal plates from which nail-like

projections are punched, with the plate projections being pressed into the opposite sides of the wooden truss members at the various joints. As previously mentioned, wooden structural trusses of this type are heavy and expensive because of the large-scale use of metal connector plates and diagonal struts to transmit stresses, usually in tension, within the truss frame in reaction to external loads.

The foregoing prior art conventional truss construction should be compared with a structural truss 30 in accordance with the invention as shown in FIG. 1. The truss 30 is composed of an upper wooden chord member 32, a lower wooden chord member 34, and vertical wooden strut members 36, but no diagonals, unlike the prior art truss construction. Furthermore, vertical struts 36 are not joined to the upper and lower chords 32, 34 by metal connector plates, or in fact by any metal fasteners whatsoever. Instead, the truss frame of FIG. 1 is covered on its opposite sides by thin, flexible membranes 38, 39, preferably of paper or other cellulose fiber material of high tensile strength.

As shown in FIG. 3, each membrane 38, 39 has a heat curable adhesive backing 40 which joins the membranes to the opposite side surfaces of the chords and struts so that the membranes join the struts and chords together into a relatively rigid truss framework.

When the flexible membranes 38, 39 are made of paper, they are preferably coated or impregnated with a protective material for weatherproofing and to retard deterioration with age. Papers or other thin, flexible membrane material are selected according to tensile strength to meet design considerations. The size of the various chord and strut members are similarly selected. For most residential and light commercial building applications, the chord and strut members would usually be made from standard 2×4 dimension lumber. The membranes could be composed of a kraft-type paper of high tensile strength. In some applications, 1×4 lumber would be suitable for the struts because of the high compressive strength of wood under column loading, which would be the primary type of loading of such struts in the truss of the invention.

Although a box truss is illustrated, pitch roof and other types of trusses could also be manufactured in accordance with the invention.

In use, it is assumed that the truss will be loaded externally along the top chord. Under this ideal condition and uniform loading, the chords and struts will be in compression, with the membranes transmitting stresses in tension.

METHOD OF MANUFACTURE

FIG. 4 illustrates a method of manufacturing the box truss of FIG. 1 by a high-speed assembly line technique. A pair of continuous chord lengths 50, 51 proceed horizontally along parallel paths downstream from a continuous finger-jointing machine (not shown) which forms the continuous lengths. At a first station 52 a paper membrane 53 is applied to the underside of the chords by a pressure roll 54 after an adhesive backing is sprayed onto the paper at 55 as it is unrolled from its supply roll 56.

The continuous membrane-backed chord lengths proceed from the first station to a second station 58 where a magazine 59 inserts precut strut members 36 downwardly between the continuous chord lengths 50, 51 and on top of the adhesive backing of membrane 53.

From second station 58 the membrane-backed chord lengths with spaced struts therebetween proceed to a third station 60 where a second pressure roll 61 applies the second membrane 62 to the upper faces of the chords and struts after an adhesive backing is sprayed onto the membrane at 63 as it is unrolled from its supply roll 64.

Thereafter the loosely assembled continuous truss frame proceeds to a fourth, curing station 66 where a microwave or other suitable energy source 67 is used to cure the adhesive and thereby secure the membranes and other truss frame elements together.

From the curing station the now one-piece continuous frame proceeds to a fifth, cutting station 68 where a knife 69 cuts the continuous truss frame into sections of predetermined length to form multiple box trusses ready for use. A pair of end struts are placed side-by-side between the chord lengths at points where the lengths are to be cut so that each resulting truss is complete when cut.

The truss as described is inexpensive as previously mentioned because of several factors. One of these factors is low material cost. The paper required for the truss is less expensive than the wood components it replaces. Furthermore, standard 2×4's can be used for the compression members of the truss. Additionally, glue replaces expensive metal plates or nails as the fastening agent.

A second factor is low production cost. Paper can be used more efficiently than wood because a roll of paper having the exact dimensions necessary for a given truss can be used in feeding the paper membrane onto the truss frame in accordance with the method of the invention. On the other hand, a relatively rigid material, such as plywood, if used as the skin or membrane would have to be cut from a standard 4×8 or other standard size sheet, resulting in much waste of material. Similar waste results from using wood diagonal strut members in a conventional truss.

A third cost factor is the low shipping and handling costs that result. The relatively light weight of the paper reinforced truss provides easy handling in the shop and

in the field, and reduces packaging and shipping costs. Such lightweight trusses should also require smaller, less expensive types of handling equipment or at least should be less abusive to existing equipment.

5 A fourth cost factor is the efficient use of materials provided by the truss and method of the present invention. Paper, which has a high tensile strength, is used as the principal tension component of the truss. Thus there is less waste in that materials such as wood having 10 high tensile and compressive strengths are not used in applications where only high tensile strength is required.

The paper reinforced truss described also has other advantages and features not necessarily limited to cost 15 as follows:

First, the paper reinforced truss provides structural design flexibility. The truss can be designed to fit the job. It does not have to be overbuilt to apply to many different applications.

20 Second, the paper reinforced truss provides visual design flexibility as well as structural flexibility. The shape of the truss can be changed with the paper sheathing concept more easily than with conventional techniques.

25 Third, the paper membranes present unlimited graphic, color and texture possibilities independent of structural considerations.

Fourth, a resin impregnation of the paper membranes would probably be necessary or at least desirable to 30 provide resistance to moisture attack which could weaken the tensile strength of the membrane. Such resin impregnation would also help prevent or at least retard degradation of the paper because of its sulfur content. It is believed that the sulfur content of paper reacts with atmospheric oxygen to cause ultimate paper failure. The resin would serve as a shield in this regard. In any event, ultimate paper failure should occur only after a period of time which would greatly exceed the expected life of the building itself.

40 Although the paper reinforced truss of the invention has been described for use in building applications, such structural trusses on a smaller scale could also be used in lighter structural applications such as in furniture construction.

45 Having illustrated and described what is presently a preferred embodiment of the invention, it should be apparent to those skilled in the art that the same permits of modification in arrangement and detail. We claim as 50 our invention all such modifications as come within the true spirit and scope of the following claims.

We claim:

1. A structural truss for use as a load-supporting and transmitting structural building component supported in a vertical plane at its opposite lower ends and free-spanning a distance between said ends, said truss including

60 an upper rigid wooden chord member defining the length dimension of said truss and adapted to receive vertically applied external loads from above, a lower rigid wooden chord member spaced vertically below said upper chord member and adapted to be supported from below at its opposite ends to receive at said ends vertically applied external reaction loads from below and to free-span a distance between said ends,

65 a plurality of rigid wooden strut compression members extending vertically between said upper and

lower chord members at spaced intervals along the length of said chord members with the opposite ends of said strut compression members abutting inside edges of said chord members at butt joints to define a structural framework,

the length dimension of said truss as defined by the length of said chord members being substantially greater than the height dimension of said truss as defined by the vertical distance between said chord members,

a pair of thin, flexible continuous tension membranes covering the opposite sides of said framework,

and adhesive means affixing said flexible tension membranes to the faces of said upper and lower chords and to the faces of said strut compression members in a manner such that said membranes provide the sole interconnection between said chord members and said strut members and such that said membranes resist external loads applied to said framework in tension,

said flexible tension membranes comprising weather-resistant paper sheet material.
